United States Patent Office

Des. 226,490
Patented Mar. 13, 1973

226,490

SKI

Robert Mimeur, Cluses, France, assignor to Etablissements Carpano et Pons, Cluses, France

Filed Feb. 3, 1972, Ser. No. 223,407

Term of patent 14 years

Int. Cl. D21—02

U.S. Cl. D34—14 D

FIG. 1 is a perspective view of a ski showing my new design;

FIG. 2 is a top plan view thereof, the bottom being conventional;

FIG. 3 is a side elevational view thereof, the opposite side being a mirror image thereto.

I claim:

The ornamental design for a ski, as shown and described.
